UNITED STATES PATENT OFFICE

OTTO KRELL, OF BERLIN-DAHLEM, GERMANY

APPARATUS FOR LANDING AIRSHIPS

Application filed July 16, 1926, Serial No. 122,995, and in Germany August 14, 1925.

My invention relates to apparatus for landing airships.

According to a generally prevailing opinion mooring towers or poles have in comparison with rotary hangars the advantage that the landed aircraft upon the mooring tower is less endangered by vertical gusts than during a landing in which the airship is directly housed in the rotary hangar. The lateral 10 guidance of the airship behind the rotary hangar has proved perfectly safe in practice. The influence of vertical gusts on the other hand becomes the more objectionable the greater the size of the aircraft. This applies particularly to airships of the rigid type which are more sensitive to a contact with the ground than those of the non-rigid type. The combination of a mooring tower with a stationary hangar would have the disadvantage that under certain conditions, for 20 instance when the direction of the wind is unfavorable the airship might have to wait a long time moored to the tower until it would be possible to house it in the station- 25 ary hangar with favorable wind.

My improved landing apparatus eliminates these difficulties by providing a floating hangar or one adapted to turn on the solid ground with a mooring tower or pole at the leeward end.

The mooring tower or pole is according to my invention provided with suitable gear, such as pulley blocks or travelling crabs, which facilitate the lowering of the point of 35 attachment of the aircraft from the point of the tower down to the opening of the hangar so that the airship may be safely housed in the hangar.

In order to render the airship less sensitive against vertical gusts, it is best to unload it as far as possible at its rear end, i. e. to give it there the highest possible buoyancy while simultaneously hauling up and suspending at this rear end a chain-link like 45 combination of ballast weights which are attached to a rope or the like. During the descent and ascent of the airship along the tower the balancing weights will be piled up upon the ground and lifted off again, alternately relieving and loading the rear portion

of the airship and thus counteracting the vertical gusts of wind. By means of my improvised apparatus the airship firmly moored with its point to the vertical guiding structure may be protected against the effect of 55 vertical gusts of wind, hauled down and housed in the hangar independent of the wind prevailing at the time.

If a floating hangar is used the balancing bodies must of course, be likewise constructed 60 as floating bodies.

In the drawing affixed hereto some embodiments of my invention are diagrammatically illustrated by way of example. In the drawing: 65

Fig. 1 represents a side elevation of the landing apparatus with the airship moored to the point of the tower,

Fig. 2, represents an additional mooring of the unloaded rear portion of the airship 70 with the ground, and

Fig. 3, represents the airship in the position ready for housing in the hangar or shelter.

Like parts are indicated by like letters of 75 reference throughout all the figures of the drawing.

Referring to the drawing 1. is the hangar, shelter or shed for housing the aircraft provided with a mooring or landing tower or 80 pole 2. 3 is the airship itself which is moored to the point of attachment 4 of the landing tower 2. The point of attachment 4 may be lowered down to approximately the middle of the opening or gate of the hangar. 85 5 are the ballast bodies which may be constructed as balls, floats or the like and which are attached to the rope 6 at definite distances apart. These ballast bodies are attached to the unloaded rear end of the airship at the point 7 and are hauled up whereby a stabilization of the airship is brought about. 90

By hauling down the point of attachment 4, the airship is brought into the position shown in Fig. 3 in readiness for running into 95 the hangar 1 in which she can now be housed comfortably.

Various modifications and changes may be made without departing from the spirit and the scope of the invention, and I desire, there- 100

fore that only such limitations shall be placed thereon as are imposed by the prior art.

I claim as my invention:

1. Landing apparatus for aircraft comprising in combination, a floating hangar, a mooring tower mounted upon the leeward end of said hangar, means for lowering the point of attachment of the aircraft from the point of said tower to about the middle of the hangar opening, and a chain of floating ballast bodies attached to the unloaded rear end of the moored aircraft.
2. In an arrangement for landing and housing airships in combination a hangar movable to place its entrance accurately leeward, a mast mounted upon the leeward entrance of said hangar, a device vertically movably mounted on said mast and having means for attaching the airship to it, and means for lowering the attached airship by said device from its attaching position at the mast to substantially the middle of said hangar entrance.
3. Apparatus for landing and housing aircraft comprising in combination a hangar movable to place its entrance accurately leeward and a mooring tower mounted upon the leeward entrance of said hangar, means for mooring the craft on said tower, and means for lowering said mooring means from the attaching point on said tower to about the middle of said hangar entrance, and a chain of ballast bodies attached to the unloaded rear end of said aircraft during the mooring operation.

In testimony whereof I affix my signature.
OTTO KRELL.
